UNITED STATES PATENT OFFICE.

CHARLES ANDREW BENDER, OF HARRISBURG, PENNSYLVANIA.

ROTARY ENGINE.

No. 904,749.

Specification of Letters Patent.

Patented Nov. 24, 1908.

Application filed July 20, 1908. Serial No. 444,342.

To all whom it may concern:

Be it known that I, CHARLES ANDREW BENDER, a citizen of the United States, residing at Harrisburg, in the county of Dauphin and State of Pennsylvania, have invented a new and useful Rotary Engine, of which the following is a specification.

This invention relates to rotary engines, and has for its principal object to provide a rotary motor in which friction is reduced to the minimum, and the steam utilized to the best advantage, the live steam being employed for direct action during a portion of the stroke and afterwards used expansively.

15 A further object of the invention is to provide a motor of this type having a combined roller valve and abutment that is held tightly against the periphery of the piston under steam pressure.

20 A still further object of the invention is to provide a combined roller valve and abutment in which said valve and abutment may be practically balanced, provision being made for the admission of steam behind the 25 valve to counter-act the pressure to which it is exposed in the working space of the cylinder.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

40 In the accompanying drawings:—Figure 1 is a vertical section of a rotary engine constructed in accordance with the invention. Fig. 2 is a sectional plan view of the same on the line 2—2 of Fig. 1. Fig. 3 is a partial transverse section on the line 3—3 of Fig. 2. Fig. 4 is a detail section showing one of the roller valves and abutments in a different position. Fig. 5 is a detail perspective view of 45 one of the valve chambers showing the location of the ports.

Similar numerals of reference are employed to indicate corresponding parts throughout the several figures of the drawings.

50 The engine is mounted on a suitable sole plate and standard 10, and the single piece

cylinder casting 11 is bored out to form a cylinder 12, and a pair of valve or abutment spaces 13 which intersect the cylinder. At the top of the cylinder casting are connections for a steam pipe 14, and an exhaust pipe 15, which lead to ports hereinafter described. To the opposite sides of the central portion of the casting 11 are secured 60 bearings 16 for the reception of a horizontal shaft 18 having at one end a balance wheel 19 and at the opposite end a gear wheel 20. On the center of the shaft is secured the hub of a cylindrical piston drum 21, the web which connects with the hub being preferably spoked and the central portions of the side walls of the main casting being, also, spoked or provided with openings in order to permit free circulation of air through the central portion of the engine 75 for cooling purposes.

The periphery of the piston drum fits over a pair of inwardly extending annular flanges 23 that form part of the main casting, and the peripheries of these flanges are 80 provided with annular grooves for the reception of packing rings 24, which spring outward into engagement with the inner surface of the rim of the piston and rotate therewith, these rings serving to prevent the 85 escape of steam from the working space of the cylinder. The opposite ends of the valve chambers or chests 13 are closed by removable heads 27 and 28, both of which are provided with stuffing boxes arranged 90 for the passage of shafts 29 and the head 27 having a bearing bracket 30 forming an additional support for the shaft. Each shaft 29 carries a cylindrical valve 31 which also acts as an abutment, and the valve is somewhat longer than the width of the piston rim, as shown in Fig. 2, and is of a diameter 95 equal to one-half the diameter of the piston drum, so that for each rotation of the latter each of the valves will be rotated twice. At 100 the end of each shaft 29 is a pinion 33, both pinions intermeshing with the central gear 20, and the pitch lines of the pinions being of the same diameter as the valves, while the pitch line of the gear is of the same diameter 105 as the drum in order that these parts may be kept in proper relative position without sliding friction.

The piston is provided with a pair of diametrically opposed wings 34, so shaped as to 110 accurately follow the curved inner wall of the cylinder, and the cylindrical valves are

provided with curved ports 35 of such size and shape as to permit the passage of the piston wings, the ports serving, also, to control the inlet of the steam or other actuating fluid.

It will be noted on reference to Fig. 2 that the length of the piston wings and the ports 35 is less than the width of the piston rim, so that during the time the wings are passing 10 the ports, the periphery of the cylindrical valve proper may rest in rolling contact with the rim. The main steam port 40 branches at 41 and leads to both valve chambers 13. At the valve chambers the ports are extended 15 around the inner wall of said chamber, as indicated at 43, at points both above and below the entrance from the main steam ports, so as to permit the pressure of steam against those faces of the cylindrical valve directly 20 in alinement with the three shafts 18 and 29, the idle or pocket portions 45 of these ports being widened transversely in order to secure the desired area, so that the steam may act effectively in forcing the cylindrical 25 valves against the periphery of the piston drum, and in a measure counterbalance the pressure exerted against that portion of the periphery of the valve exposed to pressure in the working space of the cylinder. In 30 addition to the inlet ports, a pair of auxiliary ports is arranged around each of the valve chambers. Each of these ports 46, as shown in Fig. 3, extends around the upper portion of the chamber from the vertical 35 plane of the axis of shaft 29 down to a point below and some distance outside of the vertical plane of such axis, and there communicates with a port 47 leading into the working space of the cylinder. The function of these 40 ports is twofold. They permit steam to enter from the working space of the cylinder and from the main port 43 by way of the valve port 35, and the pressure of this steam is utilized in counter-acting the pressure exerted on the exposed faces of the valve, and especially the pressure to which that portion 45 of the valve acting as a stationary abutment is exposed. These ports, also, act in connection with the ports 35 of the valve to permit 50 the passage of steam from the inlet to the working space of the cylinder. Leading from the working space of the cylinder on one side of each abutment is an exhaust port 55 15, and this port is at all times open to the outer air, condenser, or other point of discharge.

In operation, the parts being in the position shown in Fig. 1, the piston wings are 60 passing the combined valves and abutments and no steam is entering from the inlet ports to the cylinder. By the time the piston and valve reach the position shown in Fig. 4, steam is allowed to pass from the port 43 65 through the valve port 35, into the working

space of the cylinder behind the piston wing, and the valve then acts as a fixed abutment against which the steam acts in forcing the piston wing to travel in the direction indicated by the arrow. The flow of steam into 70 the working space of the cylinder continues long after the cylinder port 35 passes beyond the position shown in Fig. 3, and is only cut off when the point *x* of the valve port passes the point *y* of the pocket 45 in Fig. 3, for 75 the reason that up to this time the port 43 and pocket 45 which are in direct communication with the inlet are placed in communication with the auxiliary ports 46 and 47 through the valve port 35. During the remaining portion of the stroke, the steam will 80 act expansively.

It will be seen that the combined valves and abutments are counter-balanced to such an extent that sliding friction is almost 85 wholly eliminated, and the combined valve and abutment at each side is pressed firmly against the rim of the piston drum where rolling friction only is encountered, so that the engine may be rotated at very high speed 90 without undue heating.

What is claimed is:—

1. In a rotary engine, a ported cylinder, a piston arranged therein and provided with a projecting wing, a cylindrical abutment 95 arranged to roll on the surface of the piston and provided with a port for the passage of the wing, the length of the port being less than the width of the piston, said port serving as a means for controlling the flow of 100 steam into the cylinder.

2. In a rotary engine, a ported cylinder, a revolute piston drum mounted therein and provided with a projecting wing, a revolute abutment mounted for rolling contact 105 with the piston drum and provided with a steam port of a length less than the width of the piston, the port serving for the passage of the piston wing, and controlling also the inlet of steam or other actuating fluid 110 to the cylinder, and gearing connections between the piston drum and the abutment.

3. In a rotary engine, a ported cylinder, a revolute piston mounted therein and provided with a projecting wing, a revolute 115 abutment ported for the passage of the wing, said port being arranged to place the cylinder ports in communication with the working space of the cylinder, the wall of the receiving chamber of the abutment being provided with recesses in the rear of said abutment for the admission of a portion of the actuating fluid to thereby counter-balance 120 said abutment.

4. In a rotary engine, a ported cylinder 125 provided with a piston receiving chamber and an abutment receiving chamber, a piston drum provided with a projecting wing, a cylindrical abutment arranged for rolling contact with the periphery of the piston 130

drum, the abutment having a steam port, which permits the passage of the piston wing, said port serving also to place the cylinder ports in communication with the 5 working space of the piston chamber, the inlet ports being extended around a portion of the inner wall of the abutment chamber to permit counter-balancing pressure of the abutment, there being an auxiliary recess 10 formed in the inner wall of the abutment chamber for counter-balancing purposes, said auxiliary recess being in free communication with the working space of the piston chamber and being placed in communication 15 with the cylinder port by the port of the abutment.

5. In a rotary engine, a cylinder provided with inlet and discharge ports and having a central piston receiving chamber and abut- 20 ment receiving chambers that intersect the piston receiving chamber, a revoluble piston drum having a pair of diametrically opposed projecting wings, a pair of cylindrical abutments each provided with a steam port of a 25 length less than the width of the piston drum, the ports serving in connection with

the cylinder ports to control the flow of steam or other actuating fluid into the cylinder of the engine, shafts carrying the piston and the abutments, and extending out 30 through the wall of the casing, and gears connecting the three shafts.

6. In a rotary engine, a cylinder having movable head members, the central portions of which are provided with inwardly ex- 35 tending annular flanges, said flanges having peripheral grooves, a shaft, a piston drum secured to the shaft, the rim of the drum ex- tending in opposite directions over the two annular flanges, packing rings mounted in 40 the grooves and held expansively against the inner surfaces of the piston drum flanges, and abutments co-acting with the piston wing in the operation of the engine.

In testimony that I claim the foregoing 45 as my own, I have hereto affixed my signature in the presence of two witnesses.
